PYROPHORIC LIGHTING MECHANISM

Louis V. Aronson, Newark, N. J., assignor to Art Metal Works, Inc., a corporation of New Jersey

Original application February 24, 1936, Serial No. 65,265. Divided and this application May 25, 1937, Serial No. 144,598

4 Claims. (Cl. 67—4.1)

My invention relates to pyrophoric lighting mechanism of the type utilizing a torch for actuating the sparking device thereof.

In accordance with my invention, the force applied by the torch of the pyrophoric lighting mechanism is transmitted to the sparking unit in an advantageous manner by any one of a plurality of improved devices.

Various other objects, advantages and characteristics of my invention will become apparent from the following description.

My invention resides in the pyrophoric lighting mechanism, features, combinations and arrangements of the character hereinafter described and claimed.

This application is a division of my application Serial No. 65,265, filed February 24, 1936.

For an understanding of my invention and for an illustration of some of the forms thereof, reference is to be had to the accompanying drawing, in which:

Figure 1 is a plan view showing my invention; Fig. 2 is a vertical sectional view, partly in elevation, and is taken on the line 2—2 of Fig. 1 looking in the direction of the arrows;

Fig. 3 is a vertical sectional view, partly in elevation, of the mechanism illustrated in Fig. 2 with some of the parts shown in different positions;

Fig. 4 is a vertical sectional view, partly in elevation, of a modified form of the invention;

Fig. 5 is a plan view of the arrangement shown in Fig. 4; and

Fig. 6 is a vertical sectional view, partly in elevation, of the mechanism illustrated in Fig. 4 with some of the parts shown in different positions.

In the form of my invention shown in Figs. 1, 2 and 3, M1 represents a main casing which, in any suitable manner, is associated with a fuel casing F1. The main casing M1 comprises a top wall 40 serving, in the manner hereinafter described, as a support for the various parts of the pyrophoric lighting mechanism.

As herein shown, the lighting mechanism of Figs. 1, 2 and 3 comprises a serrated wheel 41 which is freely rotatable on a pin or axle 42 horizontally disposed in standards 43 upstanding from and secured to the top casing wall 40. Co-actable with the serrated wheel 41 is the usual pyrophoric element 44 which, in part, projects from a tube 45 suitably anchored in position interiorly of the main casing M1, said tube 45 containing a helical spring, not shown, maintained under compression in the usual manner so as to

bias the pyrophoric element 44 into engagement with the serrated wheel 41.

Disposed in side-by-side relation with respect to the serrated wheel 41 is a pinion 46, this pinion being loosely mounted upon the pin 42 the same as the serrated wheel 41. Coactable with the pinion 46 is a gear segment 47a forming the terminal portion of one arm of a lever 47 pivoted at 48 on a member 49 anchored in suitable manner to the top casing wall 40. The other arm of the lever 47 terminates in an elongated slot 47b which receives a pin 50 horizontally anchored in a plunger 51 which is mounted for vertical reciprocatory movement in a tubular member 52 secured to and depending from the top casing wall 40. As shown, the tubular member 52 is formed with aligned elongated slots 52a through which the pin 50 extends, an arrangement of this character permitting vertical reciprocatory movement of the plunger 51. As appears from a consideration of Fig. 2, the plunger 51 is suitably biased in an upward direction, as by a helical spring 53.

Any suitable arrangement such, for example, as described in application Serial No. 65,265, filed Feb. 24, 1936 may be provided for clutching the serrated wheel 41 to the pinion 46 when the latter is moved in a counter-clockwise direction, Fig. 2, under the control of the lever 47, such arrangement, as will be understood, permitting the pinion 46 to slip with respect to the stationary serrated wheel 41 when said pinion 46 is moved clockwise, Fig. 3.

In operation, a torch T of suitable character is withdrawn from its seat and placed in engagement with a depression 51a formed in the upper end of the plunger 51. Then, by the application of downward pressure, the plunger 51 is moved downwardly from its Fig. 2 position to the position thereof shown in Fig. 3. In so doing, the pin 50 rides in the slots 47b, 52a and causes the lever 47 to swing from its Fig. 2 to its Fig. 3 position. As a result, the serrated wheel 41 is given a step of movement in a counter-clockwise direction, Fig. 2, to thereby produce a shower of pyrophoric sparks which are projected toward and into engagement with the exposed end of the wick 30 as the torch T is moved downwardly in the manner described. In this way, a freely burning flame is produced at the end of the torch T and, when this flame has served its intended purpose, said torch may be seated in and on the casing M1.

Upon removal of the torch T from the tubular member 51, the latter rises under the influence

of the spring 53 and returns the parts to their normal positions as shown in Fig. 2.

It will readily be understood that movement of the torch T transmits energy directly to the serrated wheel and that such energy is not stored in any spring, or equivalent. As a result, a stream of pyrophoric sparks are produced for an appreciable period of time and, since the fuel-charged wick is passed through these sparks, it necessarily results that the desired burning flame is quickly and efficiently produced. In the appended claims, the references to the transmission of force "directly to said sparking wheel" shall be understood as describing the transfer of force through a mechanical connection and as excluding the storage of such force in a spring, or equivalent.

In Figs. 4, 5 and 6, I have illustrated an inventive arrangement wherein the shower of pyrophoric sparks is produced suddenly by release of the energy stored in a spring. Thus, in said Figs. 4, 5 and 6, M2 represents a main casing with which, in suitable manner, a fuel casing F2 is associated. The main casing M2 comprises

25 a top wall 10 which, in generally the same manner as hereinbefore described, forms a support for the various parts of the lighting mechanism.

Upstanding from the top casing wall 10 are the spaced standards 11 which support a pin or 30 member 72 horizontally fixed in position thereon. The member 72, in freely rotatable manner, supports a pair of side-by-side wheels 73, 74, the wheel 73 being a pinion and the wheel 74 being serrated on its outer peripheral surface so as to 35 be coactable with a pyrophoric element 75 which, in part, projects from a tube 76 extending downwardly through the main casing M2 and anchored thereto, the tube 76, as well known in the art, containing a helical spring, not shown, suitably maintained under compression so as to bias the pyrophoric element 75 into engagement with the serrated wheel 74.

Coactable with the pinion 73 are the gear teeth 77a forming the end of a lever 77 mounted for 45 pivotal movement on a pin 78 supported by a plate 79 secured to and depending from the top casing wall 10, the lever 77 being suitably biased in a clockwise direction, Fig. 6, as by a helical spring 80 having one end secured to the plate 79 and 50 the other end thereof secured to said lever 77.

Mounted for vertical reciprocatory movement in the top casing wall 10 and in an angular section 79a of the plate 79 is an actuating member 81 which, at its upper end, terminates in an angular section 81a movable along a vertical path disposed above the top casing wall 10 and said angular section 81a having a depression 81b formed therein for the reception of the lower end of a torch and this depression being in line 55 with the plane of the wheel 74. The actuating member 81 is biased in an upward direction from the position shown in Fig. 6 by a helical spring 82 which is confined between the angular plate section 79a and a shouldered section of the actuating member 81.

In accordance with the invention, the actuating member 81 is adapted to be connected to the lever 77 so that energy may be transferred from said actuating member 81 to said lever 77. 70 The mechanism for accomplishing this purpose may be of any suitable character and, as herein shown, such mechanism comprises a lever 83 which is pivoted at 84 to the actuating member 81, said lever 83 being biased in a clockwise direction, Fig. 6, by a leaf spring 85, or equivalent.

The lever 83 terminates in a notched end which coacts with a notched wheel 86 mounted for rotatable movement on a pin 87 extending horizontally from the plate 79, the wheel 86 also being coactable with a lateral section 77b of the lever 77.

Normally, the parts are positioned as shown in Fig. 4 wherein the lever 83 is illustrated as coacting with the lower surface of the top wall 10 to prevent further upward movement of the member 81 under the influence of the spring 82. When thus positioned, the lower end of the rod 31 of the torch T, or equivalent, may be disposed in the depression 81b of the actuating member 81 and said member 81 lowered to the position shown in Fig. 6. In so doing, the lever 83 remains in engagement with a notched surface of the wheel 86 and causes said wheel to move in a clockwise direction, Fig. 6. As the wheel 86 thus moves, an inclined surface 86a thereof engages 20 the lever section 77b and causes the lever 77 to swing in a counter-clockwise direction, Fig. 4, with resultant expansion and storage of energy in the spring 80.

As will readily be understood, a clutch mechanism is interposed between the two wheels 73 and 74 and, when the lever 77 moves as just described, the arrangement of this clutch mechanism is such that the pinion 73 idles with respect to the serrated wheel 74 which remains stationary at this time.

Eventually, as the wheel 86 moves a further slight increased distance in a clockwise direction beyond the position shown in Fig. 6, the aforesaid inclined surface 86a of the wheel 86 35 becomes disengaged from the lever section 77b whereupon the lever 77, by a snapping action, moves, under the influence of the spring 80, in a clockwise direction from the position shown in Fig. 6. As a result, the pinion 73 is rotated counter-clockwise, Fig. 6, and, by the clutch mechanism last described, said pinion 73 causes the serrated wheel 74 to move similarly in a counter-clockwise direction, Fig. 6, whereby a shower of sparks are produced and projected toward the 45 wick at the lower end of the torch T which, meanwhile, has assumed the position shown in said Fig. 6.

The torch T may now be used for igniting a pipe, cigarette or for such other purpose as may 50 be desired. As soon as said torch is removed from the actuating member 81, the latter rises under the influence of the spring 82 and all of the parts take a position such as illustrated in Fig. 6 wherein the mechanism is in condition for 55 subsequent operation as desired.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. A pyrophoric lighter comprising a receptacle, a sparking device mounted in fixed position on said receptacle and comprising a sparking wheel and a pyrophoric element biased into engagement therewith, a lever disposed interiorly of said receptacle and connected to said sparking device, means for biasing said lever in a direc- 75

tion to actuate said sparking device, a movable actuating member for said sparking wheel having a torch-engageable portion located in the path of sparks projected from said sparking wheel, and a notched wheel intervening between said actuating member and said lever.

2. A pyrophoric lighter comprising a receptacle, a sparking device mounted in fixed position on said receptacle and comprising a sparking wheel and a pyrophoric element biased into engagement therewith, a lever disposed interiorly of said receptacle and connected to said sparking device, means for biasing said lever in a direction to actuate said sparking device, a movable actuating member for said sparking wheel having a torch-engageable portion located in the path of sparks projected from said sparking wheel, a notched ratchet wheel intervening between said actuating member and said lever, a pawl connection between said actuating member and said ratchet wheel, and a pawl connection between said lever and said ratchet wheel.

3. A pyrophoric lighter comprising a receptacle, a sparking device mounted in fixed position on said receptacle and comprising a sparking wheel and a pyrophoric element biased into engagement therewith, whereby upon rotation of said wheel, sparks are projected to one side thereof, a lever disposed interiorly of said receptacle and connected to said sparking device, means for biasing said lever in a direction to actuate said sparking device, a movable actuating member for said sparking wheel having a torch-engageable portion, so located that torch means applied thereto will be in the path of said sparks, a notched ratchet wheel intervening between said actuating

member and said lever, a pawl connection between said actuating member and said ratchet wheel, and a pawl connection between said lever and said ratchet wheel, whereby each downward movement of said actuating member by application of torch means thereto first causes said ratchet wheel to turn and move said lever against its biasing means, the ratchet wheel then releasing said lever for operating said sparking device with a snap action. 5

4. A pyrophoric lighter comprising a receptacle, a sparking device mounted in fixed position on said receptacle and comprising a sparking wheel and a pyrophoric element biased into engagement therewith, whereby upon rotation of said wheel, 10 sparks are projected to one side thereof, a lever disposed interiorly of said receptacle and connected to said sparking device, means for biasing said lever in a direction to actuate said sparking device, a depressible slidably actuating member 15 extending downwardly into the receptacle from a point adjacent the path of said sparks, said actuating member being adapted to be engaged at its upper end by a manually applied torch means, a ratchet wheel in said receptacle between said lever and said slidable member, pawl means on said lever and on said slidable member for engaging said ratchet wheel, whereby each downward movement of said slidable member by application 20 of torch means thereto first causes said ratchet wheel to turn and move said lever against its biasing means, the ratchet wheel then releasing said lever for operating said sparking device with 25 a snap action. 30
